Des. 222,859
Patented Jan. 18, 1972

222,859

VEHICLE BODY

Pierre A. Delisle, Loretteville, and Yves Anselme
La Pointe, Valcourt, Quebec, Canada, assignors to
Bombardier Limited, Valcourt, Quebec, Canada

Filed June 29, 1970, Ser. No. 23,729

Claims priority, application Canada June 15, 1970

Term of patent 14 years

Int. Cl. D12—13

U.S. Cl. D14—24

FIG. 1.

FIG. 2.

FIG. 3.

FIG. 4.

FIG. 1 is a perspective view illustrating the front and one side of the design;

FIG. 2 is a side elevation view of the design;

FIG. 3 is a front view of the design; and

FIG. 4 is a rear view of the design.

The side opposite to that shown in FIG. 2 is a mirror image thereof. The elements shown in broken lines are included for illustrative purposes only.

We claim:

The ornamental design for a vehicle body, as shown and described.
